DESIGN FOR A LAMP OR LIKE ARTICLE

Sol Goodman, New York, N. Y., assignor to Goody
Lamp Co. Inc., New York, N. Y., a corporation of New York

Application October 23, 1940, Serial No. 96,094

Term of patent 3½ years

To all whom it may concern:

Be it known that I, Sol Goodman, a citizen of the United States and a resident of the county of Bronx, city and State of New York, have invented a new, original, and ornamental Design for a Lamp or Like Article, of which the following is a specification, reference being had to the accompanying drawing, forming part thereof,

The figure is a perspective view of a lamp showing my new design, the same being characterized by elongated crystals extending respectively from coil spring sockets in the manner illustrated.

I claim:

The ornamental design for a lamp or like article, substantially as shown and described.

SOL GOODMAN,
